UNITED STATES PATENT OFFICE.

GEORGE A. KEENE, OF LYNN, ASSIGNOR TO FRANCIS A. BROWN, OF CHELSEA, MASSACHUSETTS.

RECLINING-CHAIR.

SPECIFICATION forming part of Letters Patent No. 244,463, dated July 19, 1881.

Application filed January 26, 1881. (No model.)

To all whom it may concern:

Be it known that I, GEORGE A. KEENE, of Lynn, in the county of Essex and State of Massachusetts, have invented a new and useful Improvement in Reclining-Chairs, of which the following is a specification.

In the accompanying drawings, in which similar letters of reference indicate like parts, Figure 1 is a perspective view of a reclining-chair embodying my improvement. Fig. 2 is a similar view of the parts which operate the back of the chair and portions of the chair.

A represents the frame of the seat; B, the back, and C the arms. On each side of the chair, near the back, is a strong piece, D, of the shape shown, said pieces being firmly secured to the seat-frame A and helping to support the arms. Rigidly secured to these blocks D are the links E, to which is pivoted at e the back B.

Pivoted at f to the seat-frame are the levers F, which pass up from the seat-frame, spring into openings g in the racks G, secured to the under sides of the arms C, and bend through the curved slots H to the outer sides of the arms, where they terminate in handles F'.

K is a connecting-bar, pivoted at k' to the back, and at k to the spring-lever F, one such bar being on each side of the chair. When the back is nearly upright the spring ratchet-levers F are in the rear notches, g. To lower the

back, press the handles F' inwardly, thus releasing the spring-levers F and dropping them in the notches g desired. When the chair-back is at its lowest its lower edge rests against the blocks D, as seen in Fig. 2. Its pivotal point is at e.

The absence of springs and the simplicity of the mechanism afford strength and permanence, and the position of the handles make the operation of the back simple, easy, and natural to the occupant of the chair.

If desired, springs may be placed in the spaces or pockets between the lower end of the back and the blocks D, so as to act as cushions, thus preventing the back from violently striking the blocks when it drops to its lowest point. Of course the notches in the rack G may be as numerous as desired.

Having thus fully described my invention, what I claim, and desire to secure by Letters Patent, is—

The combination, with the back B, blocks D, and links E, of the bars K, spring ratchet-levers F, pivoted to the frame A, and racks G secured to the arms, all substantially as and for the purpose described.

GEORGE A. KEENE.
